UNITED STATES PATENT OFFICE

ADAM CRAIGON, OF TORONTO, ONTARIO, CANADA, ASSIGNOR TO CRAIGON ENGINES
LIMITED, OF HAMILTON, CANADA

INTERNAL-COMBUSTION ENGINE

Application filed August 9, 1928. Serial No. 298,524.

This invention relates to internal combustion engines in which the flow of the working fluid is controlled, in part at least, directly by the piston, and particularly to engines of the uniflow type disclosed in my co-pending application of even date herewith. In the said application a construction is shown in which a combustion chamber is formed in axial alignment with the engine cylinder, the end of the combustion chamber being formed by a piston valve controlling communication between a port and the combustion chamber. A port in the engine cylinder remote from the combustion chamber is controllable by the piston.

In the present invention my object is to provide a construction particularly adapted for use with twin cylinders, either single acting, or of the double acting type shown in my prior United States application 230,656, dated November 2, 1927.

I attain my object by means of a construction which may be briefly described as follows. Between a pair of cylinders is formed a combustion chamber. One wall of this chamber is formed by a piston valve which is movable in a cylindrical guide having a port in its wall, the valve being adapted to control the communication between the interior of the engine cylinder and the said port. The construction, without other change than the omission of one cylinder and the parts appertaining thereto, is also applicable to a single cylinder engine.

The invention is hereinafter more fully described and is illustrated in the accompanying drawings in which

Fig. 1 is a vertical section of an engine constructed in accordance with my invention, parts not concerned with the invention being omitted;

Fig. 2 a cross section on the line 2—2 in Fig. 1; and

Fig. 3 a longitudinal section of a modified form of valve.

In the drawings like numerals of reference indicate corresponding parts in the different figures.

In the drawings I show the engine block formed with two cylinders 1, arranged side

by side, so that two pistons may operate on a single connecting rod. In each cylinder is longitudinally movable a trunk piston 2, the sleeves 3 of these pistons being connected by a cross head carrying a gudgeon pin 4 of the connecting rod 5, the lower end of which is journalled on a crank of the crank shaft 6 in the ordinary manner. Within the sleeve of each trunk piston is located a stationary piston 7. Each stationary piston is preferably supported from the cross member 8 of the engine base.

From the construction of the cylinders and the stationary and movable pistons described, it follows that the engine is double acting.

Between the cylinders, at opposite ends thereof, I form two combustion chambers 9 and 10, each communicating with both cylinders. Between the cylinders is formed a cylindrical guide 11 in which are movable the piston valves 12 and 13. Through the wall of the cylindrical guide are formed the ports 14, each communicating with a manifold 15 (see Fig. 2 and also Fig. 1 in which a port is shown co-incident with the passage 16). Communication between these ports and the interior of the engine cylinders is controlled by the piston valves, each piston valve being provided for that purpose with a passage 16 having a plurality of radially directed passages 16^a, the passage 16 being open at opposite ends through the sides of the valve. The passages 16^a are adapted to communicate with the interior of the sleeves 3. Between the valves extends a cam shaft 17 provided with the cam 18 adapted to engage anti-friction rollers 19 on the piston valves. The piston valves are connected by the springs 20 tending to maintain the rollers in contact with the cam. The cam shaft will be driven in any known manner to actuate the piston valves.

It will be noted, on reference to Fig. 1 of the drawings, that, when a piston valve is in position to form a communication between the cylinders and one of the ports 14, the combustion chamber is reduced to vary small dimensions and is substantially closed off from communication with the cylinders. When the cylinders are closed off from communi-

cation with one of the ports 14, a combustion chamber of good proportions and shape is provided communicating easily with the ends of the cylinders. To give suitable shaping, the opposite walls of the combustion chambers are concaved, as shown, while the ends of the pistons are preferably convexed. The ends of the stationary pistons are also preferably curved, as shown, to facilitate travel of the air or gases. The closed position of each valve is determined by means of the shoulder 21 formed on the valve adapted to engage the shoulder 22 formed on the cylindrical guide. Centrally of the sleeves 3 are formed ports 23^a adapted to communicate with ports 23 formed in the cylinders, the ports 23 being in communication with the manifold 24. The ports 23 are adapted to be controlled by the pistons 2. Openings 25 are formed leading into each combustion chamber. These openings are intended for the reception of spark plugs if the device is to be employed with a gaseous fuel mixture, or for the connection of fuel valves if the device is to be used as a two-stroke cycle Diesel engine. Assuming the latter, the mode of operation is as follows:

With the parts in the position shown in Fig. 1, scavenging air is flowing through the ports 23 and passes in parallel through the cylinders and through the passages 16^a, 16 in the lower piston valve and thence to the lower manifold 15. The piston valve closes and the trunk pistons continue their descent, thus compressing the scavenging air into the combustion chamber 10, into which fuel is injected at the proper moment. Near the end of the firing stroke and before the ports 23 are uncovered the lower piston valve is opened to permit exhaust to take place. The exhaust is through manifold 15 and is driven out and followed by the fresh scavenging air from the manifolds 24 through ports 23, 23^a. The operation at the other ends of the cylinders is substantially similar.

From the above description it will be seen that, as the flow of gases is in parallel through the cylinders to a common exhaust, the engine will be operable at a higher rate of speed and scavenging will be more efficient than in the engine shown in the patent hereinbefore referred to. The engine may also be operated with the manifolds 24 acting as the exhaust manifolds, and the manifolds 15 as the inlet manifolds. When manifold 24 is used for admitting scavenging air and 15 for exhaust, however, the piston valves have to open to permit exhaust before ports 23 are uncovered to admit the air; therefore, it is necessary, or advisable at least, to reduce the load on a piston valve before it is moved to bring the passage 16 into communication with the ports 14. For this purpose I form an opening through the wall of each piston valve, which forms one wall of the adjacent combustion

chamber, and control this opening by means of the poppet valve 26. The stem of this valve is adapted to be acted on by a cam 18^a carried by the cam 18, so that the poppet valve will open just before movement is imparted by the cam to the piston valve. 70

As the piston valve closes slightly in advance of the closing of the scavenging ports 23, 23^a, a supercharging effect is obtained.

What I claim as my invention is:

1. In an internal combustion engine, the combination of a cylinder; a piston movable therein; a combustion chamber laterally offset relative to, and having a port communicating with, the cylinder; a piston valve so forming one wall of the combustion chamber; a cylinder parallel to the engine cylinder forming a guide for the piston valve and having a port in its wall, the said piston valve being adapted to control the communication between said port and the interior of the engine cylinder; and a port in the main cylinder wall remote from the combustion chamber and controllable by the piston, the piston and piston valve being adapted to move in opposite phase, whereby the combustion chamber is reduced to its smallest dimensions at the time the port in the main cylinder wall is open. 75

2. In an internal combustion engine, the combination of a cylinder; a piston movable therein; a combustion chamber laterally offset relative to, and having a port communicating with, the cylinder; a piston valve forming one wall of the combustion chamber; a cylinder parallel to the engine cylinder forming a guide for the piston valve and having a port in its wall, a port being formed through the piston valve adapted to form a passage between the port in the valve cylinder wall and the port communication with the engine cylinder; and a port in the main cylinder wall remote from the combustion chamber and controllable by the piston. 100

3. In an internal combustion engine, the combination of two parallel cylinders; a piston for each of said cylinders; a common combustion chamber located between the cylinders and communicating therewith; a piston valve forming one wall of the combustion chamber; a cylinder forming a guide for said piston valve having a port in its wall, the said piston valve being adapted to control the communication between the said port and the interiors of the engine cylinders; and a port in each engine cylinder wall remote from the combustion chamber and controllable by the piston, the pistons and the piston valve being adapted to move in opposite phase whereby the combustion chamber is reduced to its smallest dimensions at the time the ports in the main cylinder walls are open. 110

4. In an internal combustion engine, the combination of a cylinder; a piston movable therein; a combustion chamber communicating with one end of the cylinder; a piston 130

valve forming one wall of the combustion chamber; a cylinder forming a guide for said piston valve having a port in its wall, the said piston valve being adapted to control the communication between said port and the interior of the engine cylinder; a port in the engine cylinder wall remote from the combustion chamber and controllable by the piston; a passage through the piston valve forming a communication between the combustion chamber and the port in the valve cylinder wall; and a poppet valve controlling said passage.

5. In an internal combustion engine, the combination of a cylinder; a piston movable therein; a combustion chamber laterally offset relative to, and having a port communicating with, the cylinder; a piston valve forming one wall of the combustion chamber; a cylinder parallel to the engine cylinder 10 forming a guide for the piston valve and having a port in its wall, the said piston valve being adapted to control the communication between said port and the interior of the engine cylinder; a port in the engine cylinder 15 wall remote from the combustion chamber and controllable by the piston; a passage through the piston valve forming a communication between the combustion chamber and the port in the valve cylinder wall; and a poppet valve controlling said passage.

6. In an internal combustion engine, the combination of two cylinders, side by side; pistons movable therein; a combustion chamber formed between and common to the two 20 cylinders; a passageway adapted for communication with the combustion chamber; and means, forming one wall of the combustion chamber, for controlling the communication between said passageway and the combustion chamber, said means being movable in opposite phase to the pistons, whereby the combustion chamber is reduced to its smallest dimensions when the pistons are at the 25 end of their power stroke.

45 Signed at Toronto, Ontario this 29th day of June, 1928.

ADAM CRAIGON.
